(57) **CLAIM**

We claim the ornamental design for a bendable track for suspension of curtains, as shown and described.

DESCRIPTION

FIG. 1 is a perspective view of a bendable track for suspension of curtains;

FIG. 2 is an end view thereof;

FIG. 3 is a top view thereof; and,

FIG. 4 is a side view thereof.

Portions of the figures have been shown broken away to indicate that no particular length for the track is claimed.
